R. A. Moore

By *J. H. Moore*, Attorney

UNITED STATES PATENT OFFICE.

RICHARD A. MOORE, OF BROOKINGS, OREGON.

COMBINATION TOOL.

1,421,287.

Specification of Letters Patent. Patented June 27, 1922.

Application filed May 11, 1921. Serial No. 468,637.

To all whom it may concern:

Be it known that I, RICHARD A. MOORE, a citizen of the United States, residing at Brookings, in the county of Curry and State 5 of Oregon, have invented certain new and useful Improvements in Combination Tools; and I do hereby declare the following to be a full, clear, and exact description of the invention, such as will enable others skilled in 10 the art to which it appertains to make and use the same.

This invention relates to new and useful improvements in combination tools and has for its primary object the provision of means 15 whereby several types of wrenches may be provided for use on round, rectangular, and octagon-shaped stocks, and when not employed as a wrench may be adjusted to form a hammer having means for removing nails 20 and the like and also for removing dirt and grease from machinery.

Another object of this invention is the provision of means whereby the jaws may be easily and quickly adjusted in relation to 25 each other and when adjusted to an object will be locked against accidental movement relative to each other.

A further object of this invention is the provision of means whereby the device may 30 be used as a socket wrench and also a screwdriver.

A still further object of this invention is the provision of a tool of the above stated character which will be simple, durable, and 35 efficient, and which may be manufactured and sold at a comparatively low cost.

With these and other objects in view as will become more apparent as the description proceeds, the invention consists in certain 40 novel features of construction, combination, and arrangement of parts as will be hereinafter more fully described and claimed.

For a complete understanding of my invention, reference is to be had to the following description and accompanying drawings, in which:—

Figure 1 is a side elevation of a combination tool constructed in accordance with my 50 invention,

Fig. 2 is a vertical sectional view illustrating the same,

Fig. 3 is a transverse sectional view illustrating the means of slidably securing the 55 sections of the handle together,

Fig. 4 is a detail view illustrating a com-

bined screwdriver and socket wrench for attachment to the jaws, and

Fig. 5 is a detail sectional view illustrating a cotter-key remover attached to the 60 handle of the wrench.

Referring in detail to the drawings, the numeral 1 indicates a handle including parallel sections 2 and 3 having flat opposing faces provided with teeth 4 adapted to have 65 interlocking connection with each other for the purpose of holding the sections 2 and 3 against relative movement endwise in relation to each other.

The section 2 is provided with a slot 5 to 70 receive a bolt 6 secured to the section 3, and this bolt is adapted to have threaded thereon a wing-nut 7 for the purpose of preventing separation of the sections 2 and 3 and which will permit adjustment of said sections relative to each other in an endwise direction 75 by releasing the tension of the wing-nut 7 against the section 2. The section 2 also has formed therein a groove 8 which communicates with the slot at one end and is 80 adapted to receive a dove-tailed lug 9 secured to the section 3 for the purpose of preventing said sections from moving out of parallel relation during their adjustment relative to each other. One end of the section 2 is provided with a socket 10 to receive a stud 11 on the section 3 to further aid in preventing relative separation of the sections 2 and 3. When it is desired to adjust 85 the sections 2 and 3 endwise in respect to each other, the wing-nut 7 is turned on the bolt 6 to disengage the section 3 and one end of the groove 8 is slightly enlarged to permit the lug 9 to move out of said groove consequently permitting a partial separation 90 of the sections 2 and 3 and sufficient to permit disengagement of the stud 11 from the socket 10 and with the stud 11 disengaged from the socket, the sections 2 and 3 may be then adjusted endwise with respect 95 to each other.

Jaws 12 and 13 are formed integrally with corresponding ends of the sections 2 and 3 and have their opposing faces serrated as illustrated at 14 to facilitate the gripping of 100 a nut or the like and also pipes and other round articles. The ends of the jaws 12 and 13 have flat faces so that when said jaws are moved in close relation or against each other, an efficient striking face is provided 105 permitting the tool to be used as a hammer. The jaw 12 projects beyond one

side of the handle for the purpose of forming a claw 15 adapted to be used in removing or extracting nails and the like and also may be employed for removing dirt and 5 grease from machinery.

The jaw 13 at its junction with the section 3 of the handle 1 is cut away as illustrated at 16 to cooperate with one face of the jaw 12 and one face of the section 2 in forming 10 a socket 17 when said jaws 12 and 13 are in abutting engagement, and is adapted to receive a shank 18 which has one end beveled to form a screwdriver 19 and its other end has formed thereon a socket member 20 to 15 receive a nut or the like consequently permitting the device to be used in removing nuts that are countersunk.

The section 3 is provided with a screw-threaded opening 21 in its end to receive a 20 screw-threaded member 22 to which a hook 24 is secured. The hook 24 is especially designed for removing cotter-keys and the like from bolts and other parts of machinery.

25 The handle 1 is provided with graduations to facilitate the adjustment of the jaws to an object and also permit the device to be used for measuring.

While I have shown and described the 30 preferred embodiment of my invention, it will be understood that minor changes in

construction, combination, and arrangement of parts may be made without departing from the spirit and scope of the invention as claimed.

35

Having thus described my invention, what I claim is:—

1. A tool comprising a handle including a pair of parallel sections and one of said sections having a slot and a groove communicating with the latter, a bolt carried by the other section and extending through the slot, a member threaded to said bolt, a lug formed on the last-named section and received by the groove, and jaws carried by 40 said section.

2. A tool comprising a handle including a pair of parallel sections and one of said sections having a slot and a dovetailed groove communicating with the latter, a bolt 50 carried by the other section and extending through the slot, a member threaded to said bolt, a lug formed on the last-named section and having a dovetailed head fitting in said groove, and jaws carried by said sections. 55

In testimony whereof I affix my signature in presence of two witnesses.

RICHARD A. MOORE.
